CLAIM

I claim the ornamental design of shorts, as shown and described.

DESCRIPTION

FIG. 1 is a front view of the shorts showing my new design. The broken line showing is for illustrative purposes only and forms no part of the claimed design;

FIG. 2 is a front elevational view of a second embodiment of the shorts thereof;

FIG. 3 is a front elevational view of a third embodiment of the shorts thereof;

FIG. 4 is a side elevational view of FIG. 1;

FIG. 5 is a side elevational view of FIG. 2; and,

FIG. 6 is a side elevational view of FIG. 3.

1 Claim, 6 Drawing Sheets

FIG. 1

FIG. 2

FIG. 4
